FIBER ROLL FORMER

Thomas C. Taggart, Hanover, Pa.

Application July 12, 1944, Serial No. 544,605

10 Claims. (Cl. 19—158)

1

This invention relates to improvements in fibre roll formers.

The primary object of this invention is the provision of mechanism for the forming of fibres, such as flax, hemp and jute into rolls as the fibre is fed thereto in strip form from a drawing frame.

A further object of this invention is the provision of a fibre or sliver roll forming machine having improved means for controlling the fibre ribbon, strip or sliver so as to accurately form the same into a roll of desired diameter without any looseness of the ribbon or strip thereon.

A further object of this invention is the provision of an improved machine for the forming of fibre rolls from strips of fibre such as flax, hemp or jute in which the roll width is accurately controlled to present smooth sides without any unevenness of the fibre strands.

A further object of this invention is the provision of improved means for controlling the application of rolling forces upon the fibre ribbon of a roll forming machine.

A further object of this invention is the provision of an improved method for the formation of fibre rolls.

Other objects and advantages of the invention will be apparent during the course of the following detailed description.

In the accompanying drawings, forming a part of this specification, and wherein similar reference characters designate corresponding parts throughout the several views—

Figure 1 is a side elevation, partly in section, showing the improved roll forming machine.

Figure 2 is a plan view (partly in section) of the improved roll forming machine.

Figure 3 is a fragmentary view, partly in section, showing a detent and trip mechanism by means of which additional tension or drag upon the ribbon of fibre is controlled.

Figure 4 is a fragmentary cross sectional view taken thru the roll forming part of the machine substantially on the line 4—4 of Figure 1.

Figure 5 is a fragmentary view, partly in section, taken substantially on the line 5—5 of Figure 2.

Figure 6 is a fragmentary view showing a counterbalance mechanism mainly utilized for the purpose of returning the parts of the mechanism to the original position after removal of the roll.

2

Figure 7 is a fragmentary cross sectional view taken substantially on the line 7—7 of Figure 2, and also showing the fibre or material in the machine in the process of forming a roll.

Figure 8 is a cross sectional view taken transversely thru a guide trough or conductor substantially on the line 8—8 of Figure 7.

Figure 9 is a detail of a connecting link used for detachably connecting the roll forming drum or spool with the force applying portion of the mechanism.

In the drawings, wherein for the purpose of illustration is shown only a preferred embodiment of the invention, the letter A may generally designate the improved roll forming machine. It may include a drum, spool or core B upon which a roll is formed, supported by a frame or mounting construction C. A sliver or strip conductor D is provided upon the frame C for the purpose of controlling the width, depth and feed of the ribbon or strip of material from a drawing frame E to the roll forming drum, spool or core B. Means F is provided for controlled application of pressure upon the material as it is formed into a roll upon the drum B.

The drum, spool or core B is preferably of wood, metal, plastic or any other approved material which is sufficiently strong and yet without excessive weight, so as to enable the convenient handling of the rolls. It is provided with a transverse opening 10 therethru adapted to detachably receive a shaft 11. The latter, as shown in Figures 2 and 4 of the drawings, is provided at its outer ends with enlarged head or flanged portions 12 which cooperate with connector links 13 of chain cables to be subsequently described, for the purpose of detachably supporting the drum or spool for quick release upon the frame C. In the drawings the passageway 10 has been shown as enlarged in Figure 7, to permit the passage of the flanged ends 12 of the shaft 11 therethru in order to detach the shaft 11 from the spool, so that the latter, together with the roll formed thereon, may be quickly removed upwardly thru the frame of the machine. In lieu of this construction, the passageway 10 may rather closely fit the shaft 11, if so desired, and the flanges 12 could be of ring-shaped formation, detachably connected to the ends of the shaft 11. Referring to the frame structure C, the same

includes a preferably steel supporting platform 15, including side rails 16 and 17 and end rails 18 and 19. These rails may be supported upon suitable legs 20.

A pair of shafts 21 and 22 are rotatably supported upon the rails 16 and 17 of the supporting platform in suitable bearings 23, at each side of the means provided for supporting the roll forming drum B. These shafts 21 and 22 have keyed thereon suitable roll drive wheels or members 26 and 27 respectively which are transversely fluted or grooved for the purpose of frictionally engaging the material to be wound upon the spool B in order to better rotate the spool B and form the roll thereon. These driving wheels or members 26 and 27 are preferably of metal and rather heavy in structure and they are of a width which will not necessitate their removal should it be desired to change from one width of roll to another. The shaft 21 is a drive shaft and it is connected to the shaft 22 by means of a conventional socket link chain 30^b of any conventional nature, as shown in Figure 2 of the drawings.

As part of the frame structure C, I provide a pair of side boards or walls 33 and 34 detachably and adjustably mounted upon the supporting platform 15 by means of end angle brace structures 38, and by means of intermediate angled bracing members 39 which also assist in guiding the shaft 11 as the roll is formed upon the drum B.

The guide wall 33 at one side of the roll may be divided into two parts, and similar construction provided for the guide wall 34. The wall supporting members 38 are preferably metal L's including vertical portions 44 which are detachably connected by suitable bolts to the walls 33 and 34. They furthermore include horizontal foot portions 45 which are longitudinally slotted at 46 and adjustably receive clamping bolts 47 which are threaded in the supporting platform 15. Thus the walls 33 and 34 may be laterally adjusted to the desired spacing to suit the width of the drum or spool being currently used. Of course, these walls 33 and 34 are suitably cut away to receive the driving wheels 26 and 27, since the latter are of a width which will enable the walls 33 and 34 to be relatively spaced to suit a wide range of roll widths.

The intermediate brackets 39 are of metal and include vertical angled portions 50 and angled foot portions 51. One flange of the latter is slotted at 52 to receive frame attaching bolts 53. The vertical angled portions 50 are detachably connected to the wall portions 33 and 34 by means of bolts 55. The wall portions 33 and 34 may extend full lengths along the insides of the vertical portions 50. The intermediate roll guide and wall supporting angles 39 are spaced at each side of the machine to define vertical slots or ways 60 which receive therein the ends of the shaft 11 in order to guide the drum vertically as the fibre roll is formed thereon. It is noted that the width of this space 60 is of a dimension which will permit the entire shaft 11 to pass therethru, including the head portions thereon.

It is readily apparent that by reason of the slotted construction of the foot portion of the angles or brackets 38 and 39, the walls 33 and 34 may be laterally spaced to suit the width of the roll desired.

Since the vertical portions 50 of the brackets 39 may be relatively high, as where large diam-

etered rolls are desired, the upper ends thereof may be detachably connected together by means of a bolt and sleeve construction 62, shown in Figure 1.

The connecting members 13 for retaining the shaft 11 in position are of the construction shown in Figure 9. They are elongated and intended to slide against the outer edges of the laterally projecting flange portions of the angles 50, as shown in Figures 1, 2 and 4 of the drawings. They include keyhole-shaped openings laterally therethru including the lower larger portions 70 thru which the head portions 12 of the shaft 11 may freely pass, and upper reduced portions 71 connected therewith which receive the body of the shaft 11 but will not permit the flanges or head portions 12 to pass therethru. This locks the shaft 11 in position against lateral displacement, as is quite obvious, and yet permits the shaft to rotate.

The pressure applying mechanism F is provided for the purpose of pressure holding the drum or spool B downwardly as the ribbon of fibre is being rolled thereon so as to contact the fibre roll as it is formed upon the spool with the driving wheels or members 26 and 27, for the most efficient rolling of the fibre or other material upon the spool.

In order to provide for an efficient conditioning of the ribbon or fibre material as it is rolled upon the spool and to control the accurate width thereof and the smooth sided forming of the roll, I provide the conductor D which includes a suitably curved or shaped metal body surface 80 having side guide walls 82 secured thereto in any approved manner. The body 80 and walls 82 may be integral if desired and made of plastic or any other desirable material. In the preferred instance, the body 80 is of a material to give convex or fibre contacting smooth surface. This conductor may be detachably connected as at 84 to the walls 33 and 34, or mounted in the space between these walls in any approved manner. The walls 82 are exactly spaced so that their inside surfaces determine the width of the fibre roll formed upon the spool. The lower end of the conductor D terminates just short of the high point of the wheel 26, as shown in dotted lines in Figure 1 of the drawings, and feeds the fibre ribbon to the top of the wheel 26 for arcing thereabout to the point where it is circumferentially wrapped upon the spool B. As a very important feature in smoothing the sides of the fibre roll as it is formed, I provide upon the walls 33 and 34 at the point of exit of the fibre ribbon from the conductor D, side forming strips or members 90 and 91 in the form of segments which are attached either by screws or made integral with the walls 33 and 34, as shown in Figures 2 and 4 of the drawings. The fibre ribbon as it passes from the lower end of the chute or conductor D contacts the inner surfaces of these side forming members 90 and 91, smoothing the fibres and insuring an accurate formation of a roll upon the spool B with smooth sides, free of loose or wavy fibre strands. While in Figures 2 and 4 of the drawings I have shown the sides of the spool B as spaced from the inner surfaces of the walls 33 and 34, such spacing is actually very close in the machine so as to prevent too much frictional contact and yet prevent any lateral wobbling of the roll of the spool, such as will give a wavy appearance to the sides of the fibre roll formed thereon.

The drawing frame E includes the rollers 100

and 101 which receive individual layers 102 of fibre and form them into the ribbon which is fed through the conductor chute to the spool B. The speed of shafts 21 and 22 in relation to the rollers 100 and 101 is sufficient to keep the length of ribbon fibre 103 between the drawing frame and the roll B under sufficient tension to prevent any looseness therein. The tension along this ribbon to the spool B does not have any effect in the dense winding of the ribbon upon the spool B, since pressure of the fibre as it rolls upon the spool B incident to the force providing means F, to be subsequently described, is responsible for the compact and efficient forming of the roll upon the spool or drum B.

Referring to the force providing means F, the same includes a framework or platform structure 110 rotatably supporting a pair of shafts 111 and 112 in suitable bearings 113. The shaft 111 is provided with a pair of keyed wheels 115 and 116 having suitable flexible cables 120 and 121 respectively trained thereover. Each wheel 115 and 116 is provided with an apertured ear 123 receiving an adjustable bolt 124 which is connected with the cable at one end thereof, as shown in Figure 5. Any slack or play in the cable may thus be taken up. The cables are trained rearwardly, downwardly and under the wheels 115 and 116 and extend under suitable guide pulleys 130^a; the latter being pivoted in the platform structure 15 of the roll supporting frame; the cables from that point extending upwardly for connection with the connector link portions 13 above described.

A drag type of brake mechanism is associated with the shaft 111. Due to the cable connections 120 and 121 with the shaft 111 and the roll forming drum shaft 11, as the roll increases in diameter, there will be a tendency, by reason of this pressure, to compact and efficiently form the roll.

The drag type brake mechanism includes a wheel 130 which is peripherally grooved. It is keyed upon the shaft 112. The shafts 111 and 112 respectively have large and small gears 133 and 134 keyed thereon, as shown in Figures 2 and 5 of the drawings, which are in ratio to provide the necessary pressure to form the roll.

The brake arrangement includes a preferably steel or metal band 140 keyed at one end on a suitable bracket 141 secured to a foundation upon which the machine is mounted, as shown in Figure 1; the other end having a detachable weight 142. The band 140 is provided with a friction providing band 144, preferably of leather fabric or other band material which operates in the groove of the wheel 130 to apply the necessary drag.

A guide cylinder 146 is provided for the weight 142, to guide the vertical reciprocation thereof. This cylinder may be mounted upon the foundation provided for the machine, as shown in Figure 1.

In order to release the drag upon the wheel 130, I provide a manually-operated foot lever 147 pivoted at 148 upon the base or foundation of the machine; one end of the lever operating beneath the weight 142 so that the latter can be lifted and release the drag upon the wheel 130. Of course, the weight is detachable. One very important function of this pressure providing mechanism is that the weight 142 may be lifted when the roll is detached from the cables 120 and 121 to release the drag and permit return positioning of the cables to start a new roll.

The shaft 111 is provided with a drum or wheel 150 thereon, which is keyed thereto and has a

cable 152 trained thereover; the cable extending upwardly over a pulley 154 rotatably mounted at 155 upon the upper end of a frame bracket 156; the opposite end of the cable 152 having a counterweight 157 thereon. This counterweight will normally tend to apply some tension upon the cables 120 and 121 and assist in pressure application of the fibres upon the roll against the wheels 26 and 27. However, the main pressure upon the fibres being wound upon the drum or spool is incidental to diametrical size increase of the roll as it is formed, tending to rotate the brake wheel 130 against the drag imposed thereon. The main function of the counterweight 157 is to return the cables 120 and 121 to a resetting position of the spool when it is desired to start the formation of a new roll thereon. This is a very quick and efficient manner of resetting the device and avoids much manual labor which otherwise would be necessary.

It is apparent from the foregoing that the amount of drag imposed upon the wheel 130 and the pressure application of the fibre on the roll against the drive wheels 26 and 27 may be varied by increasing or decreasing the weight 142 and varying the ratio of the gears 133 and 134.

Under some circumstances, as where the roll grows to a certain size, it may be necessary to apply additional drag. This is automatically provided for in an auxiliary device. While this need not necessarily be provided, it is regarded as rather essential in connection with the winding or rolling of certain types of materials upon the spools. Thus, where springy fibres are being formed into rolls, more pressure is required against the fibres being formed on the roll at a certain point in the forming of the roll.

The auxiliary drag imposing device consists of a lever 170, which is of rectangular frame formation pivoted at one end at 171 upon a standard 172. This lever straddles the rotating wheel 130 and at its opposite end receives a detachable weight 174.

The steel band portion 140 of the brake band structure is provided with a screw threaded bolt stem 180, welded thereto as at 181, and extending tangentially downward from the wheel so as to be spaced from the band portion which supports the weight 142, as shown in Figure 1. A pair of adjustable nuts 185 are adjustably threaded on the bolt stem 180 beneath the frame 170, and a pair of nuts 186 are adjustably threaded on this shank above the lever 170. The lever 170 is provided with a fixed apertured cross piece 187 thru which the bolt stem 180 freely extends. It is readily apparent that if the lever 170 rests upon the nuts 185, the weight 174 will impose a drag upon the brake band structure tending to retard rotation of the wheel 130.

A detent mechanism, best illustrated in Figure 3 of the drawings, is provided, in order to support the lever 170 so that it will not impose a drag upon the wheel 130. This detent mechanism consists of a detent 190 pivoted at 191 upon a suitable standard 192. The detent engages in position beneath the lever 170, as shown in Figure 3, to hold the same aloft and prevent its weighted end from contacting the nuts 185. Thus, in this position the auxiliary drag providing device does not impose any drag upon the wheel 130.

I provide adjustable trip mechanism for tripping the detent 190 and releasing the lever so that it can impose the additional drag upon the wheel 130 tending to increase the pressure ap-

application upon the material being wound upon the drum B. This trip mechanism includes a trip member 200 having an end secured at 201 axially upon the shaft 112. The opposite end may engage the rim of the wheel 130. The radial position of the trip member 200 upon the wheel 130 determines the trip position of the wheel 130. In order to properly position the trip member 200, I provide a series of sockets 203 annularly around the hub of the wheel 130, as shown in Figure 1, which may receive a detachable pin 204 mounted upon the trip member 200, spaced from the connected end 201. Thus, the member 200 may be moved like the hand of a dial around the wheel 130 to properly position the same for tripping the detent 190 at any desired diametrical size of the roll being formed upon the spool or drum B. In Figure 3 is shown the shape of the head 210 of the detent 190. The trip member 200 has a cam action on this head 210 which will insure the tripping of the same and dropping of the lever 170 to the dot and dash position shown in Figure 1 of the drawings for application of the additional drag upon the wheel 130.

It is to be noted from Figure 3 of the drawings that the detent 190 has a counterbalance end portion 212 which normally throws the detent 190 into position for restraining dropping movement of the lever 170.

It will be readily apparent from the foregoing that when the roll is detached from the cables 120 and 121, as thru the removal of the connecting links 13 from the shaft 11, the counterweight 157 will not only return the cables 120 and 121 to a new roll forming position, but since the drag has been released thru the foot lever 147, the wheel 130 will be turned to a reset position. Pressing the foot lever 147, through bank 140 and its bolt stem nuts 185 will lift lever 170 upwardly past the detent 190 to a resetting position of the auxiliary drag.

The operation of the device will be apparent from the foregoing. As before mentioned, the wheels 26 and 27 have frictional contact with the material to be wound upon the spool. The fluting of these wheels increases the nature of this driving contact; the grooving or fluting, of course, being of such nature as not to destroy the fibres in the ribbon being rolled. The shaft 11 moves upwardly as the size of the roll increases, against resistance (offered to such increase in size) by reason of the drag mechanism above described. When the roll has reached a predetermined size, if it is desired to use the auxiliary drag, the detent will be tripped and the auxiliary drag will impose an additional resistance to rotation of the wheel 130, as above explained. When the roll has reached the desired size, which may be determined by suitable signal device (not shown), all that is necessary for the operator to do is to press the foot lever 147, releasing the drag upon the wheel 130. The connecting links 13 may then be readily lifted a short distance to align the larger portions 70 of the openings therein so the portions 13 may be slipped off of the ends of the shaft 11. Release of the links 13 will permit the counterweight 157 to wind the cables 120 and 121 back upon their respective wheels 115 and 116 on the shaft 11 to a resetting position, and the operator may then remove the roll. A new drum may be inserted; the shaft 11 being threaded thru the axial opening in the new spool and the connecting pieces 13 applied to connect the cables

120 and 121 with the shaft in the manner above described.

While I am aware that it has heretofore been proposed to wind ribbons of material upon spools or rolls, in the rope forming industry no one has heretofore been able to satisfactorily roll fibre, such as flax, hemp and jute upon drums or spools so as to properly condition the same for further treatment. Utilizing the improved method and machine herein described, I am able to compactly and efficiently roll the ribbons of fibre upon the drum in a manner which will give the desired density to the fibres, so that they will not dry out; thus improving the quality thereof. In conventional practice it is customary to permit the ribbons to drop into cans. As many as ten of these cans are necessary, due to the looseness of the ribbons dropping into the cans, to provide a fibre ribbon of the desired length. In such cases, splices are sometimes necessary which is avoided with the present roll formation. In actual use of these machines, there is a saving over the heretofore conventional methods and devices used of at least fifty per cent in labor and even a higher percentage in operating and maintenance expense, etc.

Various changes in the steps of the method of forming the roll and in the shape, size and arrangement of parts may be made to the form 30 of the invention herein shown and described without departing from the spirit of the invention or scope of the following claims.

I claim:

1. In a fibre roll former the combination of 35 a drum adapted to receive a roll of flexible ribbon-like material, drive means peripherally engaging the material as it is wound upon said drum for rolling said material upon the drum, means connected with the drum normally tending to impose pressure of the material against said drive means as the roll increases in size, side walls cooperating with the drum at the sides thereof for preventing eccentric forming of the ribbon of roll as it increases in size upon the drum, and guide members cooperatively related to the walls immediately in advance of the feed of the ribbon upon the drum having guide surfaces spaced slightly inwardly of the inside surfaces of said walls whereby to form the width of the roll slightly less than the direct spacing between the inside surfaces of said walls.

2. In a fibre roll former the combination of a 55 drum adapted to receive a roll of flexible ribbon-like material, drive means peripherally engaging the material as it is wound upon said drum for rolling said material upon the drum, means connected with the drum normally tending to impose pressure of the material against said drive means as the roll increases in size, side walls cooperating with the drum at the sides thereof for preventing eccentric forming of the roll as it increases in size upon the drum, and guide members cooperatively related to the walls immediately in advance of the feed of the ribbon upon the drum having guide surfaces spaced slightly inwardly of the inside surfaces of said walls whereby to form the width of the roll slightly less than the direct spacing between the inside surfaces of said walls, and a guide chute for feeding the ribbon between said guide members.

3. In a fibre roll forming device the combination of a frame, a pair of drive rollers mounted upon the frame, a ribbon receiving drum, means mounting the drum upon said frame for movement away from said drive rollers as the size of

the ribbon wound upon the drum increases, cable means connected with said drum, pulley means over which the cable means is trained, and means exerting pressure on said cable means for pulling the drum against said drive rollers comprising an adjustable brake drag, an auxiliary braking means, and means for tripping and rendering effective the auxiliary braking means upon said first mentioned brake drag for the application of additional pressure upon said roll as the latter reaches a predetermined size.

4. In a fibre roll forming device the combination of a frame, a pair of drive rollers mounted upon the frame, a ribbon receiving drum, means mounting the drum upon said frame for movement away from said drive rollers as the size of the ribbon wound upon the drum increases, cable means connected with said drum, pulley means over which the cable means is trained, and means exerting pressure on said cable means for pulling the drum against said drive rollers comprising an adjustable brake drag, an auxiliary braking means, means for tripping and rendering effective the auxiliary braking means upon said first mentioned brake drag for the application of additional pressure upon said roll as the latter reaches a predetermined size, and means normally acting upon said cables to return them to resetting position when the drum is removed from said cables.

5. In a roll forming device for wrapping a ribbon of flexible material upon a spool, the combination of a rotatable spool, a rotatable drive wheel adapted to peripherally engage the outer layer of the ribbon being wound upon the spool for rotating the spool and winding the ribbon thereon, means to urge said spool in the direction of said drive wheel for pressure application of the ribbon being wound thereon against said drive wheel, means to release said pressure, means to increase the application of magnitude of said pressure, detent means normally holding said last mentioned means inoperative, and trip means actuated by predetermined size formation of the roll to release said detent means for the application of the additional pressure upon the ribbon being wound.

6. In a roll forming device for wrapping a ribbon of flexible material upon a spool, the combination of a rotatable spool, a rotatable drive wheel adapted to peripherally engage the outer layer of the ribbon being wound upon the spool for rotating the spool and winding the ribbon thereon, a cable attached to said spool, a wheel remote from the spool for winding of the cable thereon, a brake wheel, means connecting the cable winding wheel with the brake wheel for rotation of the brake wheel upon rotation of the cable receiving wheel, a brake band mechanism for the brake wheel, means to apply braking of the band upon the brake wheel, means to release the braking effect, and counterweight means having operative connection with the cable winding wheel tending to wind the cable thereon.

7. In a roll forming device the combination of a drum adapted to receive a roll of flexible material, driving means to peripherally engage the material as it is wound upon said drum for rolling said material upon the drum, and means connected with the drum normally tending to impose pressure of the material against said driving means as the roll increases in size, including a frame, a rotatable shaft upon the frame, a wheel keyed upon the shaft, an operating cable operatively connected with the drum and wheel for

winding upon the latter, a second shaft rotatably mounted upon the frame, a brake wheel keyed upon said second shaft, means ratio gearing the shafts together, a brake band mechanism for said brake wheel, means to apply braking action of said band upon said brake wheel, and means to release said braking action.

8. In a roll forming device the combination of a drum adapted to receive a roll of flexible material, driving means to peripherally engage the material as it is wound upon said drum for rolling said material upon the drum, and means connected with the drum normally tending to impose pressure of the material against said driving means as the roll increases in size including a frame, a rotatable shaft upon the frame, a wheel keyed upon the shaft, an operating cable operatively connected with the drum and wheel for winding upon the latter, a second shaft rotatably mounted upon the frame, a brake wheel keyed upon said second shaft, means ratio gearing the shafts together, a brake band mechanism for said brake wheel, means to apply a braking action of said band upon said brake wheel, means to release said braking action, an auxiliary braking means for said brake band, detent means normally retaining said auxiliary means inoperative, and trip means associated with said brake wheel to trip the detent means at a predetermined point in the rotation of said brake wheel to impose additional drag upon the brake band acting upon said brake wheel.

9. In a roll forming device for the winding of a roll of flexible material, the combination of a frame, a drum rotatably supported by the frame for receiving the flexible material, rotary drive means associated with the drum and engageable with the outer peripheral roll portion of the material as it is wound upon the drum, cable means connected with the drum, a brake tending to resist movement of the cable means as the size of the roll upon the drum increases, means to release the braking effect upon said cable, an auxiliary braking means operatively associated with the first mentioned braking means, means normally maintaining said auxiliary braking means inoperative including a detent, and trip means operated at a predetermined size rotation of said roll upon the drum for tripping the detent and adding the auxiliary braking means to the effective braking action of the first mentioned brake.

10. In a roll forming device the combination of a frame, rotary drive means upon the frame, a drum associated with the drive means for receiving a roll of flexible material thereon, the frame supporting the drum so that it may bodily move towards and away from the drive means and so related to the drive means that the flexible material wound thereon will engage the drive means to rotate the drum for the rolling of the flexible material thereon, a cable connected with the drum, a wheel upon the frame upon which the cable is wound, brake means associated with said wheel normally tending to resist unwinding of the cable from said wheel as the size of the roll increases for the purpose of application of pressure upon the material wound upon the drum against said drive means, means to release the braking action of said brake means, an auxiliary weight for imposition of additional braking action upon the brake means, means normally maintaining said weight inoperative including a detent, and trip means associated with the brake means to trip said detent and normally

11

impose the force of the weight means upon the brake means to add to the braking action when the size of the material wound upon the roll reaches a predetermined diameter.
